COMPRESSORIAL WAVE DELAY MEANS

David L. Arenberg, Rochester, Mass., assignor,
by mesne assignments, to the United States
of America as represented by the Secretary of
War

Application April 2, 1946, Serial No. 659,113

8 Claims. (Cl. 178—44)

1

This invention relates to delay means and more particularly to solid delay lines that provide a relatively short time delay.

Supersonic delay lines have been employed in the past which consist of a solid medium of quartz, glass, or suitable metal in the form of a rod or bar with a piezoelectric crystal mounted on either end thereof. An electrical signal, preferably of a frequency of 10 to 30 megacycles, is applied to one of the crystals causing it to vibrate mechanically. These vibrations travel down the delay medium until they strike the second crystal. The second crystal is then set into mechanical vibration and the stresses thus caused in the crystal produce an electrical signal that may be transferred to a suitable receiving device. The received signal is substantially identical to the signal applied to the first crystal but is delayed by an amount equal to the time of travel of the supersonic energy in the delay medium.

In certain types of solid delay lines the energy is caused to travel the length of the delay medium several times in order that a longer delay may be obtained with the same physical size of line. Difficulty is encountered in these delay lines employing multiple reflections due to the fact that the beam of energy traveling through the delay medium travels substantially parallel to the axis of the rod but tends to diverge slightly as it progresses and as a result will eventually strike the boundary or side of the delay medium and rebound to the receiving crystal. This is undesirable because the path traveled by this portion of the energy striking the boundary of the medium is, in general, longer than the path of the energy that does not strike the boundary, thus not one but several delayed signals will be received from the delay line.

One method heretofore used to eliminate these undesired signals is to physically increase the size of the delay medium so that energy does not strike the side or boundary of the medium until after the desired delay has been attained. The disadvantage of this solution is that the physical size and weight of the delay medium must be greatly increased.

It is an object of the present invention therefore to provide means for suppressing undesired signals in solid delay lines without increasing the physical size of the line.

A further object of this invention is to provide a delay line of small cross section in which extraneous echoes are controlled or eliminated.

For a better understanding of the invention together with other and further objects thereof,

2

reference is had to the following description in which:

Fig. 1 is a schematic drawing of a conventional solid delay line;

Fig. 2 is a schematic drawing of a solid delay line illustrating one type of echo suppression;

Fig. 3 is a schematic drawing of a solid delay line illustrating a second form of echo suppression.

10 In Fig. 1 of the drawing there are shown piezoelectric crystals 10 and 12 placed at either end of delay medium 14.

Leads 16 electrically connected to crystal 10 provide means for applying a signal to or receiving a signal from this crystal. Leads 18 electrically connected to crystal 12 provides means for applying a signal to or receiving a signal from this crystal. For purposes of illustration only it will be assumed that a signal will be applied to

20 crystal 10 and a signal will be received from both crystal 12 and crystal 10. The signal received by crystal 12 will result from energy traveling the length of delay medium 14 only once while the signal received from crystal 10 will result

25 from a signal traveling the length of delay medium 14 until it reaches crystal 12 and there being reflected so that it travels the length of delay medium 14 a second time and strikes crystal 10.

30 The reflection at the end of delay medium 14 at which crystal 12 is located may be accomplished by employing a crystal whose acoustical impedance is not matched to the acoustical impedance of delay medium 14 or it may be accomplished through the use of suitable reflecting end cells. In Fig. 1 the primary path of the supersonic energy from crystal 10 to crystal 12 will be along the solid line 20, and the primary path of

35 energy from crystal 12 to crystal 10 will be along the solid line 22. Due to the divergence of the beam of supersonic energy as it travels through delay medium 14, secondary paths of energy from crystal 10 to crystal 12 will be along the dotted lines 24 and 26. It can be seen from Fig. 1

40 that energy traveling in paths 24 and 26 will strike the end of delay medium 14 at a slight angle with respect to the normal and will, therefore, be reflected toward the boundary of delay medium 14. In this example, energy traveling

45 along path 24 rebounds along the dotted path 28 striking the boundary of delay medium 14 at a point 30. At point 30 the energy is again reflected and travels along a path 32 to crystal

50 10. In a similar manner energy traveling along path 26 will be reflected along a path 34 striking

the boundary of medium 14 at a point 36 where it is again reflected along a path 38 to crystal 10. From the geometry of Fig. 1 it can be seen that the energy traveling along paths 24, 28, and 32 must travel a greater distance than energy traveling along the paths 20 and 22. Also, energy traveling along paths 26, 34, and 38 will travel a distance substantially equal to the distance traveled by energy in paths 24, 28 and 32 but will travel a greater distance than energy traveling in paths 20 and 22. The first delayed signal therefore that will be received at crystal 10 will result from energy traveling along the outward path 20 and the returned path 22. At a slightly later time a second echo signal will be received at crystal 10 resulting from energy traveling along paths 24, 28 and 32 and paths 26, 34 and 38. In the usual construction of solid delay lines the crystals are symmetrically placed on the delay medium so that echo signals resulting from the reflection at the boundary of the delay medium will return in phase and will result in spurious signals of the same order of magnitude as the desired delayed signal. It should be understood at this point that in delay lines longer than the one herein shown the energy may be reflected from the boundaries of the transmission medium several times before reaching the crystal. It should be understood further that there may be numerous energy paths between paths 20 and 24 and paths 20 and 26 and the undesirable echoes result from the combination of the energy at the receiving crystal from all the various paths.

Fig. 2 illustrates one method of suppressing the undesired echo signals. In Fig. 2 parts corresponding to like parts in Fig. 1 have been given the same reference numeral. Energy traveling from crystal 10 to crystal 12 will again travel along the path 20 and will be returned to crystal 10 along the path 22, therefore, the delay of the primary signal has not been altered in any manner. The boundary of delay medium 14 has been roughened by chipping or sand-blasting in two areas 40 and 42. These areas include the points 30 and 36 of Fig. 1. If delay medium 14 is circular in cross section, the chipping may be done in a band completely encircling delay medium 14. If, however, delay medium 14 is rectangular in cross section chipping on the broad surfaces only may provide sufficient suppression of the undesired signals. In Fig. 2 it can be seen that energy traveling along path 24 will again be reflected along the path 28 and will strike the roughened surface 40 of delay medium 14 at a point 44. At point 44 the energy traveling in path 28 will be reflected along some random path 46 and may under some circumstances strike the roughened area 42 and again be reflected along a random path 48. In a similar manner energy traveling along path 26 will again be reflected along path 34 and strike the roughened area 42 at a point 50. At point 50 this energy is reflected along a random path 52. In the example shown paths 48 and 52 are directed away from crystal 10 but this will not always be the case since chipping of the delay medium is a random process and some energy may be reflected toward crystal 10. The fact that some of the energy striking the boundary is returned to crystal 10 does not necessarily mean that undesired echoes of sufficient magnitude to interfere with the operation of the circuits associated with crystal 10 will be received. In this embodiment of the invention energy reflected from the boundary of delay medium 14 no longer returns in such a phase that they com-

bine to produce a signal of the same order of magnitude as the primary signal. If the surface is properly roughened cancellation of unwanted signals by destructive combination of the energy from the various paths will take place. An optimum relationship exists between the degree of roughness and the wavelength. If a very short wavelength is employed, and the chips are large, the size of the chips may be comparable to the wavelength. This condition may cause the chipped area to act as a series of small plane reflectors and thus cause undesired signals. Conversely, a fine chipping with a longer wavelength may not produce sufficient diffusion of the beam at the chipped area. The optimum relationship between wavelength and degree of roughness lies between these two extremes.

The chipping of delay medium 14 is best accomplished by applying signals to crystal 10 and displaying the delayed signals from the receiving crystal, in this embodiment the same crystal, on a cathode ray tube indicator or any similar visual display device. Delay medium 14 is then chipped or roughened in a random manner until only the primary signal remains. There is very little danger of interfering with the primary signal while performing the chipping operation because the primary paths do not extend to any point in the vicinity of the boundary of delay medium 14. In making delay mediums of quartz or glass it may be desirable to polish only the ends of the delay medium where the crystals are to be mounted, so that the amount of roughening or chipping required is reduced to a minimum. Other methods or techniques of roughening the boundary of delay medium 14 will be obvious to those skilled in the art.

Fig. 3 illustrates a second method of eliminating undesired signals in a solid delay line. Again parts in Fig. 3 corresponding to like parts in Fig. 1 are given the same reference numeral. In the embodiment of the invention shown in Fig. 3 crystal 10 is made slightly asymmetrical or is placed slightly asymmetrically on delay medium 14. The asymmetry of crystal 10 may be accomplished by placing one electrode on crystal 10 at a point other than a physical center of the crystal, by making the crystal slightly irregular in shape, or by any other convenient means. The primary path of energy from crystal 10 to crystal 12 will still be along path 20 and this energy will still be reflected along the path 22. Secondary paths 54 and 56 will now be present for energy traveling from crystal 10 toward crystal 12. Due to the asymmetry of crystal 10, energy along the paths 54 and 56 will strike the end of delay medium 14 at slightly different angles with respect to the normal. Energy along path 54 will be reflected along a path 58 striking the boundary of delay medium 14 at a point 60 where it is reflected along a path 62 to crystal 10. Energy traveling along path 56 is reflected along a path 58 and in this example does not strike the boundary of delay medium 14 before returning to crystal 10. Energy returning to crystal 10 along paths 62, 58 and similar paths (not shown) would cause echo signals of very small amplitude to be produced by crystal 10. Provided that energy along the various paths is not in phase, the undesired echo signals will have a very much smaller amplitude than the primary signal resulting from energy traveling along paths 20 and 22 and therefore will not interfere with the proper operation of the delay line and the associated circuits. Again the adjustment of this embodiment of the invention is best accomplished by applying signals to

crystal 10 and displaying the delayed signals on a visual type indicator while adjusting the asymmetry of crystal 10. When the desired results have been obtained the adjustment may be made permanent by coating the crystal with paraffin or other similar material or by fixing crystal 10 and electrodes connected to this crystal in any manner well known in the art.

It can be seen that both embodiments of the present invention employ a common operating principle; namely to so direct the path of energy within the transmission medium that energy in the various paths diverging from the normal path and striking the boundary of the medium will be so directed that destructive combination of this energy takes place at the receiving crystal rather than the constructive combination that normally takes place in conventional delay lines.

In other embodiments of the invention, boundary reflected signals may combine at crystal 12 to form unwanted signals. These signals may be eliminated in exactly the same manner that unwanted signals at crystal 10 in this embodiment were eliminated and by either of the methods herein disclosed.

While there has been described what is at present considered the preferred embodiment of the invention, it will be obvious to those skilled in the art that various changes and modifications may be made therein without departing from the invention.

What is claimed is:

1. A delay system comprising a polysurfaced solid delay line having a pair of opposed surfaces and compressional wave transducer means operatively coupled to said surfaces, at least a portion of the surface of said delay line intermediate said surfaces being roughened for attenuating compressional wave components incident thereon.

2. A delay system comprising a polysurfaced solid delay line having a transmitting surface and a receiving surface, a transmitting compressional wave transducer operatively associated with said transmitting surface and a receiving compressional wave transducer operatively associated with said receiving surface, at least a portion of the other surfaces of said delay line being roughened for attenuating compressional wave components incident thereon.

3. A delay system comprising a solid delay line having a transmitting surface and a receiving surface, a transmitting compressional wave transducer operatively associated with said transmitting surface and a receiving compressional wave transducer operatively associated with said receiving surface, the said transducers being asymmetrically disposed relative to each other for attenuating compressional wave components reflected from surfaces of said delay line other than said transmitting and receiving surfaces.

4. A delay system comprising a polysurfaced solid delay line having a transmitting surface and a receiving surface, a transmitting compressional wave transducer operatively associated with said transmitting surface and a receiving compressional wave transducer operatively associated with said receiving surface, portions of other surfaces of said delay line being roughened for attenuating compressional wave components reflected from said other surfaces, the said transducers being asymmetrically disposed relative to each other for further attenuating said attenuated components.

5. A compressional-wave delay device comprising a poly-surfaced solid delay line having a pair of opposed surfaces and compression-wave transducer means operatively coupled to at least one of said opposed surfaces, at least a portion of the surface of said delay line intermediate said opposed surfaces being roughened for the random dispersion of compressional-wave components incident thereon.

6. A compressional wave delay line comprising a solid transmission medium having at least two opposed parallel surfaces, portions of the remaining surfaces of said medium being roughened for attenuating compressional wave energy incident thereon, and compressional wave transducer means mounted on at least one of said opposed surfaces.

7. A compressional wave delay device comprising a solid compression wave translating medium having wave reflecting boundaries, compression wave transducer means coupled to at least one of said boundaries to effect application of compression waves thereto for travel through the medium in a desired direction, at least a portion of said boundaries having deformations to effect a multiplicity of dispersions of the compression waves travelling in other than the desired direction.

8. A delay device according to claim 7, wherein said deformations are of the order substantially comparable to the wave length of said compression waves.
